UNITED STATES PATENT OFFICE

EDWARD ARTHUR GEOGHEGAN, OF NEW YORK, N. Y., ASSIGNOR TO SUPERSTEAM GENERATOR COMPANY, OF NEW YORK, N. Y., A CORPORATION OF DELAWARE

SUPERHEATER FOR MARINE BOILERS

Application filed January 8, 1931, Serial No. 507,359; and in Great Britain June 2, 1930.

This invention relates to superheaters and more particularly to marine superheaters adapted for installation in marine boilers of the so-called Scotch type. Heretofore, when 5 superheaters have been installed in marine boiler installation it has been the practice to dispose the superheater elements either in the fire tubes of the boiler or in other cases the installation of the superheater has been effected in the breeching. Neither of these 10 locations afford the best disposition for the superheater.

Scotch marine boilers as heretofore constructed, have comprised one or more furnaces within the boiler shell. These furnaces extend rearward to a vertically disposed combustion chamber associated with each furnace. These combustion chambers are in turn in communication with the fire tubes of 20 the boiler. The fire tubes in turn deliver the product of combustion to the breeching. The combustion chambers were within the boiler and in a relatively inaccessible position, being surrounded by the water wall of the 25 boiler.

One object of the present invention resides in the provision of an improved superheater construction which will permit the superheater to be disposed in the combustion chamber of a Scotch marine boiler instead of requiring the superheater to be disposed elsewhere, i. e. in the fire tubes or in breeching as heretofore.

A further object of the present invention 35 resides in the provision of a superheater construction adapted for installation in the combustion space of a Scotch marine boiler in which the superheater units may be passed into the combustion space through the furnace which is associated with each combustion 40 chamber.

A further object of the present invention relates to a provision of a superheater for a 45 Scotch marine boiler in which a superheater is disposed in the combustion chamber of the boiler and in which the headers for the superheater are disposed without the combustion chamber and outside of the boiler so that they are not only accessible but also away from the 50 intense heat within the combustion chamber.

Other objects of the present invention relate to the provision of certain supplementary connections between the headers and water spaces of the boiler and certain novel arrangements of valves which will be hereinafter described in further detail.

Further and other objects of the present invention will be hereinafter set forth in the accompanying specification and claims and shown in the drawings which by way of illustration show what I now consider to be preferred embodiments of my improvement.

In the drawings:

Figure 1 is a central sectional view of a Scotch marine boiler showing my improved superheater disposed in the internal combustion space of the boiler. The view also shows a superheater unit in dotted lines in the position which it assumes in being passed into the combustion chamber;

Fig. 2 is an end elevational view, the view being taken substantially on line 2—2 of Fig. 1;

Fig. 3 is an end view of the rear water wall of the boiler broken away and the rear walls of the combustion chamber broken away to show the superheater units in full lines in the combustion chamber spaces;

Fig. 4 is a top elevational view of one of the superheater units; and

Fig. 5 is a detail view taken substantially on line 5—5 of Fig. 4, one transverse tube being shown in full and the other tubes being shown in section.

In the drawings in Fig. 1 there is shown a Scotch marine boiler provided with fire tubes 11 and with a furnace 12. The other furnaces 12a and 12b are shown in Fig. 3. The furnace 12 is in communication at its rear end with an internal upwardly extending combustion chamber 13 and the furnaces 12a and 12b are similarly in communication with combustion chambers 13a and 13b. 14 represents the rear wall of the combustion chamber 13 and 15 is the external rear wall of the boiler. As is usual in these Scotch marine boilers there is a water space 16 intermediate 15 and 14.

According to the present invention the superheater units are disposed within the inter-

100

nal combustion chambers 13, 13a and 13b. To provide openings through the water space 16 into the various combustion chambers, each combustion chamber has thimbles or sleeve-like members 17 and 18 disposed as shown in Fig. 1 and cooperating with walls 15 and 14 as shown to provide openings through the water space through which the tube ends of the superheater units may extend.

10 In Fig. 1, 19 represents a tubular superheater unit. This unit consists of a continuous tube section bent up into the configuration shown which is substantially saddle shaped having an intermediate depression at one side between the loops at the ends of the unit. Each unit also has an outlet tube end 20 and an inlet tube end 21, which extend out substantially at right angles to the unit and at their ends these tubes 20 and 21 are provided with suitable flange connections as shown. The saddle shaped configuration of each superheater unit provides sufficient clearance to permit the unit being passed into the combustion chamber through the associated furnace. This is shown by the dotted line illustration of the unit in Fig. 1.

30 By disposing the superheater units in the internal combustion chamber of the Scotch marine boiler, the superheater is subjected to intense heat and such unit does not materially restrict the flow of the hot gases enroute from the furnace to the fire tubes. The inlet and outlet headers for the various superheater units are shown at 22 and 23 respectively and such headers are disposed back of the rear water wall 15 and accordingly they are not subjected to the intense heat of the gases within the combustion chamber. Connection of the units to these headers may be made in any suitable manner preferably by the flanged connection shown.

40 It will be understood that there is a superheater unit 19a in combustion chamber 13a and another unit 19b in combustion chamber 13b (see Fig. 3).

45 Figs. 4 and 5 show the manner of bending up the tubular unit to provide for bringing out the outlet and inlet tube ends 20 and 21 in one place so that they can pass through the openings provided by the ferrules 17 and 18.

50 In the operation of superheaters, I have found it advantageous and desirable to provide for admitting regulated quantities of water from the water space of the boiler to the inlet header of the superheater. For this purpose the pipe connection 25 is provided disposed as shown in Figs. 1 and 2. This pipe connection extending through a check valve 26 and connecting at its upper end to the header 22 and its lower end to the water space of the boiler as shown. The check valve opens in the direction of the arrows. This pipe connection permits a comparative- 60 ly small quantity of water to be admitted to

the inlet header into the superheaters and this water is converted into steam in passing through the superheater.

65 I have also found it desirable to dry out the steam passing from the steam space of the boiler to the inlet header. This is preferably effected by providing a nozzle 27, Fig. 2, and a standpipe 28 in which standpipe the steam velocity is reduced. The standpipe 28 is of considerable height so that the slugs of water in the steam can have their velocity reduced so that they can fall back into the boiler. Suitable connection 29 is made from the tube of the standpipe to the inlet header 22.

70 I have also found it desirable to provide a connection pipe 30 also provided with a check valve 31 and disposed intermediate the outlet header 23 and the steam space of the boiler. This connection permits a slight flow of steam by thermo-siphonic action from the header 23 back to the steam space of the boiler.

75 The above arrangement of water supply pipes, steam transfer pipe and steam nozzle, etc., are more fully described and claimed in my copending application Serial No. 306,699, filed September 18, 1928.

80 What I claim is:

1. A superheater for a Scotch marine boiler, said boiler having a combustion chamber and a furnace leading thereto, said superheater comprising a tube unit formed from one continuous length of tubing with a multiplicity of loops and tube portions connecting said loops with a saddle shaped configuration to provide for increased length of the tubing unit while still maintaining clearance for inserting the unit into the combustion chamber through the furnace of the boiler.

85 2. An improved superheater unit comprising a multiplicity of connected loops formed of continuous tubing, adapted for disposition within the internal combustion chamber of a Scotch marine boiler, which combustion chamber is in communication with the furnace of the boiler, said multiple looped continuous tubing unit being saddle shaped to provide for greater length and area of the continuous tubing unit while maintaining clearance and to permit the inserting of the unit into the combustion chamber through the furnace.

90 3. The invention set forth in claim 2 in which extended tubular legs are provided on each unit at the ends of the tubular sections with connecting flanges permanently thereon to afford connection between the unit and supply and outlet headers which are disposed without the boiler said tubular legs comprising a single tubular inlet and a single tubular outlet for each multiple looped tubular superheater unit.

95 4. A superheater unit for a Scotch marine boiler which boiler is provided with a combustion chamber and a furnace communicating

therewith, said superheater unit being formed of continuous tubing, said unit having a single inlet end connection and a single outlet end connection with the intermediate tubing being continuous from the inlet connection to the outlet connection and comprised of a multiplicity of loops, said unit being of saddle shaped configuration to provide for a greater length of the continuous tubing loops and greater area of heat absorbing surface while affording a configuration of the unit which permits of inserting the unit into the combustion chamber through the furnace.

5. A superheater unit for installation in locations where furnace and combustion chamber proportions and configurations give restricted clearance for superheater installation when the superheater unit is installed completely assembled and fabricated, said unit being formed from a continuous length of tubing with a multiplicity of intermediate looped portions and single inlet and outlet end portions, said unit being shaped with a saddle shaped configuration to permit tilting and warping of the unit during installation in passing the unit through a restricted opening so that a unit of the saddle shaped configuration may be more readily installed than a corresponding unit which lacks the saddle shaped configuration.

In testimony whereof I hereto affix my signature.

EDWARD ARTHUR GEOGHEGAN.
